VALANCE

Bernard F. Stenz, New York, N. Y.

Application September 7, 1944, Serial No. 553,008

11 Claims. (Cl. 160—39)

1
This invention relates to valances for the decoration of the inner frames of windows in living rooms, club rooms, restaurants and interiors in general.

Among the objects of the present invention it is aimed to provide an improved valance which is adjustable for different widths of windows and at the same time readily attachable in place by the ordinary interior decorator, housekeeper or the like, thereby disposing of the services of a skilled mechanic or carpenter as is frequently necessary when installing the conventional valances today extensively used.

It is still another object of the present invention to provide an improved valance which is not only simple to install, but which is inexpensive to manufacture, maintaining to a minimum the use of so-called essentials for warfare, without in any way detracting from the ornamental effect desired, and on the contrary conducive to the production of an exceedingly luxuriant and magnificent effect.

It is still another object of the present invention to provide an improved method for producing an ornamental panel suitable for use as one or more of the panels of a valance.

These and other features, capabilities and advantages of the invention will appear from the subjoined detailed description of one specific embodiment thereof illustrated in the accompanying drawings in which

Figure 1 is a front elevation of a valance made according to the present invention.

Fig. 2 is a plan view of the same.

Fig. 3 is a section on the line 3—3 of Figure 1.

Fig. 4 is a section on the line 4—4 of Fig. 2.

Fig. 5 is a fragmental enlarged perspective of a detail of the valance.

Fig. 6 is a fragmental enlarged perspective of another detail of the valance.

Fig. 7 is a front perspective slightly enlarged of the center panel of the valance.

Fig. 8 is a rear perspective slightly enlarged of the center panel shown in Fig. 7.

Fig. 9 is an enlarged fragmental section of the center panel.

In the embodiment shown, there is illustrated a valance consisting mainly of two end pieces or panels 1 and 2, two side pieces or panels 3 and 4, and a center piece or panel 5. The end pieces 1 and 2 and side pieces 3 and 4 are preferably composed of a composition board such as cardboard. Excellent results have been achieved when the cardboard used is of the type sold under the name "Meade Chestnut Board" having a thickness of about one-eighth inch. This board was selected in part for the reason that a smooth

edge finish could be obtained suitable for receiving a waterproof lacquer, the color of the lacquer on the edge 6 of the center piece 5 may be blue, but obviously any other color may be used without departing from the general spirit of the invention.

Still furthermore, in order to simulate a textile weave and finish, such as a satin finish or the like, each of the panels 1, 2, 3 and 4 has first attached thereto a decorated sheet of paper 7. Excellent results have been achieved when the paper selected for the covering 7 was "Moistrite" offset paper. After the paper had been so secured in place on the panels 1, 2, 3 and 4, then the panels are subjected to an embossing process.

Excellent results have been achieved when the embossing effect is produced by a conventional large Sheridan embossing press, as an instance a No. 8 Sheridan embossing press. The conventional process includes producing a male and female die conformed to the design on the paper and after alining the dies in the press with the design on the paper, then to subject the paper 7 and cardboard support to the required embossing pressures by causing the two dies to impinge in accordance with conventional practice. The embossing depressions made possible when the paper is so mounted upon a cardboard support may equal depths of one-sixteenth inch and vary according to the design with excellent results. Many exquisite decorative ensemble effects have been produced by this process. As an instance, with a textile background, a luxuriant satin finish may be effectively produced with raised flowers suggestive of embroidery.

The center piece 5 preferably consists of two similarly shaped boards 8 and 9, similar to the panels 1, 2, 3 and 4 in composition. The edges 10 of the boards 8 and 9 also are preferably stained with a waterproof lacquer. The outer board 9 preferably has attached thereto a decorative paper covering 11 such as the covering 7. In actual practice the design of the center piece 5 and side pieces 3 and 4 will preferably match as illustrated, and the board 9 and paper covering 11 will be subjected to the same embossing process as that followed with the side pieces 3 and 4.

The two boards 8 and 9 are spaced from one another by the strips 12 and 13 to form a pocket 14. The exposed edges of the strips 12 and 13, to promote the ensemble decorative effect desired, preferably are stained the same color as the edges of the boards 8 and 9. In the present instance, the outer edges of the strips 12 and 13 align with the outer adjacent edges of the boards

8 and 9, while the inner edges 15 and 16 shown in dotted lines in Fig. 7 are substantially parallel to one another and spaced from one another a distance just sufficient to clear the edges of the inner ends of the side pieces 3 and 4, see Figure 1. The side pieces 3 and 4 have their inner ends slidably mounted in the pocket 14 to afford adjustment for the length of the valance effectively to correspond to the slight variations between different windows. To facilitate this slideable association, the thickness of the strips 12 and 13 approximate the thickness of the panels 3 and 4, and in some cases are slightly thicker to facilitate the slideable association.

The lower edges of the panels 3, 4 and 5 may depart from straight lines and assume various decorative curved lines of which the embodiment in Figure 1 is an example.

The panels 1, 2, 3, 4 and 5 in weight, composition and size are conformed to cooperate with the means now to be described to facilitate assembling the panels as a valance and in turn to facilitate securing the valance in place on the frame of a window or interior of a room.

As an instance, a bracket 17, preferably U-shaped as shown in Fig. 3, and composed of stainless steel one-sixteenth inch in thickness, approximately one and one-half inches wide, can be used to advantage. Excellent results have been achieved when the leg 18 secured to the wall 19 is about two inches long, the intermediate web 20 is about four and one-half inches long and the leg 21 is about one and one-half inches long. The leg 21 as shown in Figs. 2 and 3 is slid into the pocket 22 formed by the intermediate section 23 pressed outwardly from the strip 24. This strip 24 is preferably composed of "Riegel tag" stock, or "bristol board" having a thickness approximating one-thirtieth of an inch to one-sixteenth of an inch, and sufficiently springy so that its end sections 25 and 26 will have a bracing effect on the rear face of the board 8 to obstruct warping. This strip 24 may conveniently be secured to the board 8 by the staples 27, two along each edge of the intermediate extended section 23, as shown in Fig. 8.

For securing the edges of the end panels 1 and 2 in place, there are provided in the first place the brackets 28, 29 composed of any suitable rigid material such as sheet metal or a plastic such as "Vinylite."

The end brackets 28 and 29, when composed of "Vinylite" or "Lucite" are preferably about one-sixteenth inch in thickness having a base 30, see Fig. 5, with openings 31 and 32 at the ends thereof to receive suitable securing means such as nails or screws, with two outwardly extending jaws or flanges 33 and 34 flaring toward one another in their outward extent. When secured against the wall 19, the lower securing means, such as a screw or nail, preferably has a projection 35 formed thereon, so that the lower edge of the panel 1 or 2 may rest upon the same for support. Ordinarily, however, the projection 35 merely serves as a precautionary measure supplementing the means now to be described.

Preferably the main reliance for support is placed upon frictional engagement between the edges of the panels 1 and 2 and the jaws 33 and 34 of the brackets 28 and 29. To maximize the frictional grip, afforded by their embossed faces, the inner edges of the panels 1 and 2, as shown by the shading 36, are crimped. The outer edges of the panels 1, 2, 3 and 4, supplementing their embossed faces, are similarly crimped, see the

shading 37 and 38 in Fig. 6. The adjacent crimped edges of the panels 1 and 3 as one set, and 2 and 4 as the other set, are fitted in the mouths 39 and 40 formed by the pairs of jaws of each angular bracket 41, the pairs of jaws of the brackets 41 extending at right angles to one another in the present instance so as to receive the outer ends of the panels 1 and 2 disposed at right angles to the panels 3 and 4, and also to receive the outer ends of the panels 3 and 4 as shown in Fig. 2.

The brackets 41 are also preferably composed of some suitable rigid material such as sheet metal, "Vinylite" or "Lucite." When composed of "Vinylite," here too preferably the thickness of the jaws forming the mouths 39 and 40 approximate one-sixteenth inch.

The edges 10 of the boards 8, 9 and strips 12 and 13 are portrayed as blue in Fig. 7, but obviously any other color may be used without departing from the general spirit of the invention. When the edges 10 of the center piece 5 are so stained, preferably the edges of the panels 1, 2, 3 and 4 are similarly stained in a color to correspond to the color scheme of the ornamental design on the paper facing or covering 7 of the several panels.

In order to facilitate an understanding of the ornamental effect produced by the valance made according to this invention, the method of producing the ensemble effect will now be described: initially the paper covering, such as the paper covering 11, is embossed with a textile weave impression to simulate a textile surface, thereupon the design, such as flowers and petals or some artistic geometric design or the like in colors is printed on the paper, preserving the textile surface effect not only in the background, but also in the floral or geometric design, thereupon the paper 11 is mounted or secured to a cardboard support such as the board 9, and thereupon the cardboard support with the paper 11 is again subjected to an embossing process in which case not only the paper but also the cardboard is embossed, a female and male die being used one on one surface, and the other against the other surface, to produce the design in relief, here caution being exercised to emphasize the edges or outlines of the flowers and petals of the design or outlines or edges of the geometric figure constituting the design, so that the textile surface effect may still be retained with a view to producing a textile weave and finish.

It is obvious that various changes and modifications may be made to the details of construction and to the steps of the method without departing from the general spirit of the invention as set forth in the appended claims.

I claim:

60 1. In a valance, the combination of two end panels, a center panel having a chamber, two side panels having ends thereof slidably mounted in the chamber of said center panel, a support for anchoring the center panel to a supporting structure, brackets having jaws for receiving the inner edges of the end panels and anchoring the same to the supporting structure, and corner brackets having jaws, one jaw of each bracket receiving an edge of an end panel and the other jaw of each bracket receiving an edge of a side panel.

65 2. In a valance, the combination of two end cardboard panels, a center cardboard panel having a chamber, two side cardboard panels having ends thereof slidably mounted in the chamber of

70 75 said center panel, a support for anchoring the

center panel to a supporting structure, brackets having jaws for receiving the inner edges of the end panels and anchoring the same to the supporting structure, and means for securing the adjacent edges of said end and side panels to one another.

3. In a valance, the combination of two end panels, a center panel having a chamber, two side panels having ends thereof slidably mounted in the chamber of said center panel, a support for anchoring the center panel to a supporting structure, brackets for securing the end panels to the supporting structure, said end panels having inner crimped edges, said brackets having jaws to frictionally grip said crimped edges, and corner brackets each securing the edge of an end panel to the edge of a side panel, the edges of the end panels and side panels so secured being crimped, and the corner brackets having jaws frictionally to grip said latter crimped edges.

4. In a valance, the combination of two end cardboard panels, a center cardboard panel having a chamber, two side cardboard panels having ends thereof slidably mounted in the chamber of said center panel, a support for anchoring the center panel to a supporting structure, brackets of plastic material for securing the end panels to the supporting structure, said end panels having inner crimped edges, said brackets having jaws to frictionally grip said crimped edges, and corner brackets of plastic material each securing the edge of an end panel to the edge of a side panel, the edges of the end panels and side panels so secured being crimped, and the corner brackets having jaws frictionally to grip said latter crimped edges.

5. In a valance, the combination of two end panels, a center panel having a chamber, two side panels having ends thereof slidably mounted in the chamber of said center panel, a support for anchoring the center panel to a supporting structure, brackets having jaws for receiving the inner edges of the end panels and anchoring the same to the supporting structure, and corner brackets having jaws, one jaw of each bracket receiving an edge of an end panel and the other jaw of each bracket receiving an edge of a side panel, said panels being composed of cardboard, paper coverings secured to the outer faces of said cardboard and having ornamental designs thereon, the ornamental designs on said paper being embossed into the paper and cardboard support.

6. In a valance, the combination of two end panels, a center panel having a chamber, two side panels having ends thereof slidably mounted in the chamber of said center panel, a support for anchoring the center panel to a supporting structure, brackets having jaws for receiving the inner edges of the end panels and anchoring the same to the supporting structure, and corner brackets having jaws, one jaw of each bracket receiving an edge of an end panel and the other jaw of each bracket receiving an edge of a side panel, the support for the center panel consisting of a U-shaped rigid bracket, one leg of said latter bracket being secured to the supporting structure, and a pocket on the rear face of said center panel, the other leg of said bracket extending into said pocket.

7. In a valance, the combination of two end panels, a center panel having a chamber, two side panels having ends thereof slidably mounted in the chamber of said center panel, a support for anchoring the center panel to a supporting structure, brackets having jaws for receiving

the inner edges of the end panels and anchoring the same to the supporting structure, and corner brackets having jaws, one jaw of each bracket receiving an edge of an end panel and the other jaw of each bracket receiving an edge of a side panel, the support for the center panel consisting of a U-shaped metal bracket, one leg of said bracket being secured to the supporting structure, and a cardboard stapled to the rear of said center panel having bracing ends and forming an intervening pocket with said center panel, the other leg of said bracket extending into said pocket.

8. In a valance, the combination of two end cardboard panels, a center cardboard panel having a chamber, two side cardboard panels having ends thereof slidably mounted in the chamber of said center panel, a support for anchoring the center panel to a supporting structure, brackets of plastic material having jaws for receiving the inner edges of the end panels and anchoring the same to the supporting structure, corner brackets of plastic material having jaws, one jaw of each bracket receiving an edge of an end panel and the other jaw of each bracket receiving an edge of a side panel, means for securing the first named brackets to the supporting structure, and projections on certain of said securing means to serve as limiting stops for the lower of said end panels.

9. In a valance, the combination of two side cardboard panels and one center cardboard panel slidably connected to one another to adjust the same to windows of different widths, and means including brackets having jaws for receiving the outer edges of the side cardboard panels to secure the same in place.

10. In a valance, the combination of a plurality of connected cardboard panels, a paper facing secured to the outer faces of said panels, said paper facing having a textile weave effect in relief embossed therein, and means including brackets having jaws for receiving the edges of the panels and cooperating with the textile weave effect in relief frictionally to secure the panels in place.

11. In a valance, the combination of a plurality of connected cardboard panels, a paper facing secured to the outer faces of said panels, said paper facing having a textile weave effect in relief embossed therein, said paper facing having an ornamental design impressed therein while retaining the textile weave effect in relief, the cardboard panels with the paper facing being together embossed to produce in relief the ornamental design on the paper facing while retaining the textile weave effect in relief, and means including brackets having jaws for receiving the edges of the panels and cooperating with the design in relief and the textile weave effect in relief frictionally to secure the panels in place.
